UNITED STATES PATENT OFFICE.

OTTO SCHLICK, OF BERLIN, GERMANY.

PYROPHOROUS LIGHTER.

Specification of Letters Patent. Patented Mar. 31, 1914.

1,091,967.

Application filed March 3, 1913. Serial No. 751,831.

To all whom it may concern:

Be it known that I, OTTO SCHLICK, of Berlin, Germany, a subject of the King of Saxony, and whose post-office address is 5 Steinmetzstrasse 31, in the city of Berlin, Kingdom of Prussia, German Empire, have invented a new and useful Pyrophorous Lighter, of which the following is a specification.

This invention relates to pyrophorous lighters, that is to say, to lighters in which sparks are produced by rubbing a spark producing material, for instance cerium-iron or the like and a wick impregnated with inflammable liquid such as benzin or 15 the like, or a piece of tinder is lighted.

This invention relates more particularly to an improved construction of the rubbing surface in such lighters.

This improvement chiefly consists in the rubbing surface being formed in the shape of grooves, which has the advantage that the sheaf of sparks is held together better, and therefore lights more easily, as well as 25 that the rubbed sparks are more securely guided so as to prevent sliding off laterally.

Other features relate to the construction of the rubbing surface so that it is rotatable or reversible for the purpose of increasing 30 the length of life, and further that for the purpose of facilitating interchangeability or reversibility, the rubbing surface is secured in the casing by a spring support.

Figure 1 of the accompanying drawing shows a lighter according to this invention 35 in elevation, Fig. 2 shows in elevation a construction by way of example of the spring support, Fig. 3 is a plan of the lighter shown in Fig. 1, while Figs. 4-7 are plans 40 of modified constructions of the rubbing surface.

In Fig. 1, *a* is the receiver or casing of the lighter, which receives in the known manner an ignition rod *b* which can be withdrawn and rubbed against the surface arranged laterally on the casing. For that purpose, to the bottom end of the ignition rod is secured in any suitable manner, a piece *c* of spark producing material, for instance cerium-iron or the like, surrounded 50 by a wick *d* or a piece of tinder which, on the ignition rod being rubbed against the rubbing surface, is ignited. According to this invention, the rubbing surface in the 55 construction shown in Figs. 1-3, consists of two round rods *e* with rough surfaces, pref-

erably like those of a file. In the latter case, it is preferable to arrange the oblique direction of the teeth of one cylindrical file in the opposite direction to that of the other 60 file, so that sparks are produced both when rubbing the ignition rod downward or upward. Owing to the round rods *e* leaving between them a groove or channel, a lateral sliding off of the ignition rod and damage 65 to the casing is avoided, and the sheaf of sparks is held together better. The round bars or rods *e* are preferably secured by a corrugated spring support *h*, Figs. 2 and 70 3, pressing the round rods in a springy manner against the bent out edges *i* of the casing *a* and thus securing them, while at the same time enabling the two round rods to be turned relatively to each other when the rubbing surface is worn, so that any yet 75 unused portions of the surface of the rods form the rubbing surface.

In the modified construction shown in Fig. 4, the rods *e*¹ forming the rubbing surface, are of triangular, instead of circular, 80 cross-section, so that a groove or channel is again produced in the center, and prevents the ignition rod from sliding off laterally. These triangular rods *e*¹ cannot be turned, but they can be pulled out upward and then 85 turned, so that the outer triangular surfaces which have not yet been used, form the rubbing surface.

In Fig. 5, the rods *e*² instead of being of triangular shape, have a lozenge shape, so 90 that by changing the rods, four unused rubbing surfaces can be exchanged.

In Figs. 6 and 7, the groove-shaped rubbing surface consists either of two triangular rods *e*³ or of one trough-shaped rod *e*⁴. 95 In these two constructions, there is only the advantage of avoiding lateral sliding off and holding together the sheaf of sparks, while after the rubbing surface is used up, 100 a new rod must be introduced.

In the foregoing description, it has been assumed that the ignition rod *b* of the lighter contains the spark producing body *c*, while the rubbing surface formed by the rods *e* or *e*¹ *e*² *e*³ *e*⁴ is a rough surface of steel 105 or the like. It is obvious that the arrangement could be reversed. The ignition rod *b* with which the rubbing surface is rubbed, instead of containing a body of spark-producing material *c*, can contain a sharp-edged bar or a sleeve of steel, and the rods *e*-*e*⁴ forming the rubbing surface, can be 110

rods of spark producing material such as cerium-iron or the like. This reversed arrangement does not alter the substance of the invention.

5 What I claim, and desire to secure by Letters Patent of the United States, is:—

1. In an ignition apparatus in which sparks are produced by rubbing a rod against a rubbing surface, the combination 10 of a casing, an ignition rod removably inserted in the casing, said ignition rod comprising a cerium-iron part, and a steel rubbing surface arranged on the casing, said rubbing surface being depressed in part to 15 form a guiding groove for said ignition rod.
2. In an ignition apparatus in which sparks are produced by rubbing a rod against a rubbing surface, the combination 20 of a casing, an ignition rod removably inserted in the casing, said ignition rod com-

prising a cerium-iron part, and a transversely concave steel rubbing surface arranged on the casing.

3. In an ignition apparatus in which sparks are produced by rubbing a rod 25 against a rubbing surface, the combination of a casing, an ignition rod removably inserted into the casing, a grooved rubbing surface removably mounted on the casing with a spring support adapted to hold the 30 grooved rubbing surface yieldingly in its seating, substantially as set forth.

In testimony whereof I have hereunto set my hand in presence of two subscribing witnesses.

OTTO SCHLICK.
